CLAIM

The ornamental design for an air freshener doll, as shown and described.

DESCRIPTION

FIG. 1 is a front elevational view of an air freshener doll, showing my new design;

FIG. 2 is a bottom plan view thereof;

FIG. 3 is a top plan view thereof;

FIG. 4 is a rear elevational view thereof;

FIG. 5 is a left side elevational view thereof; and,

FIG. 6 is a right side elevational view thereof.

The support ribbon is fragmentarily shown in FIGS. 1-4 for convenience of illustration.

FIG. 2**FIG. 3****FIG. 1****FIG. 4****FIG. 5****FIG. 6**
